CIRCULAR KNITTING MACHINE OF THE
DOUBLE AXIALLY OPPOSED NEEDLE
CYLINDER TYPEAlfred Woodward Kent, Groby, England, assignor
to Wildt and Company, Limited, Leicester,
England, a British companyApplication May 27, 1936, Serial No. 82,109
In Great Britain June 6, 1935

21 Claims. (Cl. 66—135)

This invention relates to circular knitting machines of the double end-to-end needle cylinder type, and especially such machines having superposed rotary needle cylinders with double-ended latch needles operable by means of sliders, as exemplified in British Patent No. 24,290 of 1912.

The object of the present invention is to improve machines of the type concerned by combining therewith patterning mechanism of the kind comprising individually movable thread guides for lapping or wrapping threads around predetermined needles, such threads being additional to the main yarn or yarns ordinarily supplied, and selecting means for producing relative movement between the needles and thread guides for the purpose of obtaining lap or wrap striping or embroidery effects, such, for example, as vertical or diagonal stripes, clocks, broken, zig-zag and various other effects.

In the accompanying drawings:—

Figure 1 is a sectional elevation of the upper part of a machine of the superposed rotary needle cylinder type equipped with double-ended latch needles operable by means of sliders with which a constructional form of patterning mechanism of the kind herein described is combined.

Figure 2 shows one of the thread guides employed in this pattern mechanism.

Figure 3 is a side view on an enlarged scale of a thread guide and an associated needle in their normal positions.

Figures 4, 5 and 6 are views similar to Figure 3 showing the various stages in the lapping or wrapping of a thread around the needle.

Figure 7 is a detail sectional view taken on the line VII—VII of Figure 5.

Figure 8 is a sectional plan view taken on the line VIII—VIII of Figure 1 showing more particularly the means employed for imparting the radial movement to the thread guides.

Figure 9 is a detail sectional view taken on the line IX—IX of Figure 8 illustrating the manner in which selected thread guides are retracted.

Figure 10 is a somewhat similar view which is taken on the line X—X of Figure 8 and represents a vertically movable cam for nullifying the selective action of the pattern drum or equivalent means on the thread guides.

Figure 11 is a developed view of the nullifying and retracting cams and of cams for moving selected guides slightly towards the needles to be lapped or wrapped to facilitate the lapping or wrapping action.

Figure 12 is a rear elevational view of the up-

per part of the machine showing mechanism whereby the thread guides can be shogged laterally over one or more of the needles.

Figure 13 is a sectional plan view of the shogging mechanism taken on the line XIII—XIII of Figure 12.

Figure 14 is an elevational view of the driving member of the said mechanism.

Figure 15 illustrates the upper end of a sleeve which is keyed to the cylindrical carrier for the thread guides and shows mechanism for lifting and lowering the sleeve for the purpose hereinafter set forth.

Figure 16 is a longitudinal sectional view of said sleeve and shows in addition means, other than those shown in Figure 1, for guiding the threads from the source of supply to the thread guides.

Figure 17 is an inverted plan view of the feeder block of the machine and an associated thread guard hereinafter described.

Figure 18 is a detail sectional view, taken on the line XVIII—XVIII of Figure 12, of a half round cam for operating the said thread guard.

Figure 19 is a further elevational view of the upper part of the machine showing the aforesaid feeder block in position, together with various operating means hereinafter described in detail.

Figure 20 is a detail elevational view showing alternative means for operating the nullifying cam shown in Figures 8, 10 and 11.

Figure 21 is a detail sectional view showing a modification hereinafter to be described.

Figure 22 is a detail view showing a thread guide co-operating with one of said deflecting elements.

Figure 23 shows one of the thread guides employed in the last mentioned form of the invention.

Figure 24 is a development of the knitting cam system which is preferably used in conjunction with the form of the invention illustrated in Figures 21, 22 and 23.

Referring to the drawings, in the patterning mechanism to be described with reference to Figures 1 to 20, each of the thread guides 1 has a thread holding extremity 2 formed at right angles to the main body portion and this extremity is laterally bent or cranked, as shown more clearly in Figure 7. A thread receiving hole 3 is provided in the outer end of the extremity 2. In addition the said guide or feeder is fulcrumed at x, i. e. between its ends, and has one or more frontal butts such as 4, hereinafter referred to

55

as pressure butts, on the opposite side of the fulcrum to the thread guiding extremity 2, and a main butt 5 which projects forwards at or near the same end. The longitudinally tricked cylindrical carrier 6 for the guides 1 is mounted above and concentrically with the circle of the needles 7 to which the additional threads *a* are to be supplied. The thread receiving extremities 2 of the guides project radially from the carrier 6 at the 5 lower end thereof (see Figures 1 and 8). A vertical bank of selector levers or cams 8 is provided for action selectively upon the pressure butts 4 aforesaid, above the fulcrum points *x*, so that selected guides 1 are pressed inwards at their 10 upper ends and are projected at their lower ends, as represented at the right-hand side of Figure 1. A track or like cam 9 is provided for action upon the main butts 5 of the guides seriatim in such a manner that these are slightly lowered and 15 then raised. The cam 9, as shown clearly in Figure 11, is made up of two sections 9a and 9b and extends on either side of the selecting point *S* between the points A and B (see Figure 8). Each of the cam sections is formed with a longitudinal 20 track 10 for reception of the butts 5 of the guides and with bevelled edges 11 to provide a lead in for said butts. The section 9a is mounted in an extension 12 of the cam box 13 in such a manner 25 as to be capable of adjustment in a vertical direction, while the section 9b is rigidly secured to a bracket 14 (Figure 8) attached to the top plate or like upper part 15 of the machine. The section 9a, moreover, is positioned slightly below the section 9b and is formed with a downward projection 16, the arrangement being such that immediately a selected guide (such as *x*, Figure 11) passes the selecting point *S* in the direction of the arrow, the butt 5 thereof rides down an inclined side of the projection 16 with the result 30 that said guide is slightly lowered, i. e. moved slightly towards the associated needle to be lapped or wrapped, for the purpose of facilitating the lapping or wrapping action. The guides are re-positioned in a longitudinal direction before they 35 again reach the selecting point by means of the bevelled edges 11. The thread guiding extremity 2 of each guide is laterally bent or cranked so that said guide is deflected laterally as the result 40 of the contact of the laterally bent or cranked 45 extremity with the adjacent needle 7 during the radial movement. Each thread guide has an upwardly extending butt 17 at the upper end and, as shown in Figures 8, 9 and 11, a retracting cam 18 mounted in the cam box extension 12 is provided 50 for action upon these butts seriatim for the purpose of restoring selected guides to the normal position. A similar cam 19 which is conveniently attached to the bracket 14, may be provided to ensure that all the thread guides 1 are fully retracted before they pass the selecting point *S*. It may be mentioned here that normally the 55 lower ends of the guides 1 occupy a position just above the needle hooks at the selecting point, as shown in Figure 3. Figure 4 shows the relative positions of a guide and its associated needle 7 immediately after said guide has been projected by one of the selector cams 8. It will be observed that at this stage the thread *a* to be lapped or wrapped passes on one side only of the needle. 60 Now, before the guide is retracted by the cam 18, the associated needle rises (see Figure 5) and then the guide is retracted taking its yarn with it, during which movement the laterally bent or cranked extremity 2 of the guide engages the side 65 of the said needle whereupon the guide (and may

be also the needle) yields or is deflected laterally as indicated at *y* in Figure 7. After passing the needle 7 on the return movement, the thread guiding extremity 2 springs back to its normal position (see *z*, Figure 7) with the result that the 70 thread *a* is lapped or wrapped round the said needle, as seen in Figure 6, and is formed into a stitch when the needle next knits.

The aforesaid selecting levers or cams 8 in this constructional form of the invention are 75 operated selectively by means of a drum 20 having pins or pegs such as 21 pre-arranged therein according to pattern requirements and racked round by cam actuated pawl and ratchet mechanism. In the specific arrangement shown in Figures 1 and 8, the said cam actuated pawl and ratchet mechanism is of the character described with reference to Figures 10 and 11 of the specification of my prior British Patent No. 443,736. As will be seen, two ratchet wheels 22 and 23 having teeth of the same pitch are oppositely arranged on and rigidly attached to the drum 20, and two clawers 24 and 25 disposed so as to correspond with the opposite arrangement of the ratchet wheels are provided. These clawers are 25 controlled by springs such as 26 to impart the idle strokes to the clawers and for imparting the operative strokes to the latter there is provided a common actuator in the form of a reciprocatory slide 27 which is mounted for movement horizontally in the top of the casing of the drum 20. The outer end of the actuator is formed with two open-ended slots 27a and adjusting screws 28 are provided whereby adjustment of the clawers on the side can be effected. At its other end the 30 reciprocatory slide 27 is fitted with a roller 29 adapted to co-operate with a cam 30 screwed to the underside of a gear ring 31 which latter is arranged to drive the cylindrical carrier 6 at the same speed as the top cylinder 32 as hereinafter 35 more fully described. In order to accommodate the spindle 20a of the drum 20 during reciprocation of the slide 27, the latter is formed with a longitudinal slot 27b. Associated with the clawers 24 and 25 is an arcuate bluff member or 40 guard 34 which extends over a greater part of the periphery of, and is adapted to be moved angularly to and fro between the ratchet wheels 22 and 23. Thus by movement of the bluff member or guard in one direction or the other either of 45 the clawers can be allowed to engage its respective ratchet wheel while the other爪 is bluffed. The bluff member or guard 34 is provided with a lug 34a so as to enable it to be controlled by timing mechanism of any usual character. 50

The cylindrical carrier 6 for the thread guides 1 is rotatably mounted upon a sleeve 35 depending from a top plate or like upper part 15 of the machine, and is driven by means of toothed gearing 60 from a suitable shaft 36 at a speed equal to the cylinder speed. When it is desired to shog the circular series of thread guides the driving gear for the said carrier includes a pinion 37 freely mounted on the beforementioned shaft, and has 65 in association therewith a driving member 38 which is keyed on the shaft but is adapted for axial adjustment automatically and to act between parts or members, such as screws, on the pinion for the purpose of imparting independent 70 turning movement to the pinion as well as driving it so that the carrier 6 for the thread guides is shogged one or more times in one direction or the other to an extent equal to the pitch of the needles, according to pattern requirements. Con-

veniently, and as illustrated in Figures 12, 13 and 14, the driving member 38 consists of a reel or like member slidably keyed at 39 on the driving shaft 36 and furnished with opposed stepped cams or like formations 40 and 41 adapted respectively to be engaged by rollers 42 and 43 on a pattern controlled sliding block 44 which is movable to different positions radially with respect to the axis of the shaft 36 so that the reel 38 is moved axially on the shaft in one direction or the other to different positions according to the position to which the sliding block is moved. This reel 38 is in frictional engagement with the shaft 36 so that when thus moved it will be held by such frictional engagement in the position to which it has been moved. The cam 40 is secured by means of screws 40a to the underside of a flange 38a formed at the top of the reel, while the cam 41 is attached by screws 41a to the top of a flange 38b formed at the bottom of said reel. Mounted on the top of the flange 38a is a tongue or like projection 45 having inclined or stepped edges 45a, and the pinion 37 is furnished with opposed screws 46 for contact with the stepped edges of said tongue or like part so that the latter not only transmits the drive from the shaft 36 to the pinion, but when the reel 38 is moved axially it also turns the pinion in relation to the shaft in one direction or the other to an extent determined by the stepped edges 45a and the amount of axial movement imparted to the reel 38.

The sliding block 44 is mounted for movement horizontally in the top of a bracket 47 clamped to a vertically disposed rod 48 secured at its upper end in the top plate 15. The inner end of the sliding block is formed with an extension 44a on which the rollers 42 and 43 are mounted so as to be located in different vertical and horizontal planes. The corresponding steps of the cams 40 and 41 are off-set with respect to each other in a radial direction on the reel to suit the positions of the rollers 42 and 43 so that each is enabled to act on the respective cam as shown more clearly in Figure 12. The sliding block 44 is prevented from displacement laterally from the bracket 47 by a plate 49 secured to one side of said bracket and is normally urged towards the reel 38 in such a way as to ensure that each of the rollers engages a step on the adjacent cam by means of a spring 50 attached at one end to the outer end of the sliding block and at the other end to the plate 49. In the typical example shown in the drawings, the sliding block 44 is adapted to be controlled i. e. moved to different positions radially with respect to the axis of the shaft 36, by means of a separate series of pins or pegs 51 suitably prearranged in the same drum 20 from which the thread guides 1 are controlled. For this purpose the pins or pegs 51 are prearranged for action upon a part 52a of a lever 52 which lever is pivoted on a bracket 53 attached to the underside of the casing of the drum 20 (see Figure 1) and connected with the sliding block 44 by a rod 54. The end of the rod 54 remote from the lever 52 is attached to one arm of a small bell-crank lever 55 the other arm of which latter is adapted to engage a recess or gap 44b in the sliding block 44. The bell-crank lever is pivoted on an outwardly extending arm 41a on the bracket 47. The arrangement just described is such that the lever 52 is moved positively by the pins or pegs 51 one way or the other with the result that the sliding block 44 is moved in one direction or the other for the purpose described. As will be seen, the lever 52, as viewed in end elevation in Figure 1, is of U

formation and this enables one limb of the lever to be pivoted to an upright part of the bracket 53 on the outside of the casing of the drum 20 and the part 52a to be positioned within and parallel to the wall of said casing.

Each of the screws 46 associated with the pinion 37 is carried by a slidable bar 56 mounted for adjustment inwards and outwards in relation to the axis of the pinion so as to enable the degree of turning movement effected by a predetermined adjustment of the sliding block 44 to be varied. Referring to Figures 12 and 14 it will be seen that the upper edges of the slidable bars 56 are received in longitudinal guideways 37a formed in the underside of the pinion 37 and are adapted to be clamped to the sides of a rectangular block 37b formed integrally with said pinion by means of screws 57. To permit of the lengthwise adjustment of the slidable bars 56 the latter are formed with longitudinal slots 56a—one for each screw 57.

The threads a may be supplied to the thread guides 1 from a number of bobbins, cones, spools or reels, such as 58, carried by a bracket or like structure. This bracket or like structure is preferably arranged co-axially with the cylindrical carrier 6. According to the illustrative embodiment of the invention the bobbins are arranged in tiers about a rod 59 which extends vertically upwards from, and is mounted at its lower end in the top of a bobbin bracket 60. For the sake of convenience only one tier of bobbins has been shown in Figure 1. The bobbins of each tier are placed on spindles 61 carried by a circular support 62 having radial arms 63 formed integrally with an inner ring 64 which is associated with a hub rigidly secured on the rod 59. The threads a pass from the bobbins 58 through perforations in the ring 64 and the top of the bobbin bracket 60 and may be led to the guides 1 through any suitable guiding means arranged within the cylindrical carrier 6 as hereinafter described. Conveniently the bracket 60 is mounted to rotate on or in one or more supports such as 65 formed or provided on the top plate 15, ball or other anti-friction bearings being provided to enable the bracket to revolve freely. In the typical example shown in Figure 1, a circular carrier member 66 is screwed to the bottom of the bobbin bracket 60 and balls 67 are interposed between the member 66 and a ball race 68 carried by the supports 65. The bracket 60 is driven from the cylindrical carrier 6 by means of a sleeve 69 to which the carrier is keyed and which is furnished with a tongue or tongues such as 69a adapted to enter a recess or recesses such as 66a in the carrier member 66. The said sleeve may also be used for raising and lowering the cylindrical carrier 6 and associated parts in relation to the needles to which the threads are to be supplied. To this end the sleeve 69 may be supported by lifting and lowering mechanism in connection with the main controlling means e. g. chain or drum of the machine, and including ball or other antifriction bearings to enable the sleeve to revolve freely. This mechanism as shown in Figures 1 and 15, conveniently includes a sleeve bearing ring 70 which is arranged to surround the upper part of the sleeve 69 and is cut into halves to facilitate assembly.

The sleeve bearing ring is provided at the top 70 and the bottom with an outwardly extending flange 70a and between these flanges is located a roller 71 which is carried at one end of a lever 72 pivoted in or on a small bracket 73 fixed on the top plate 15. The end of the lever 72 remote

from the roller 71 is connected by a push rod 74 with another lever (not shown) acted upon by cam bits or like elements on the pattern drum or chain of the machine. The roller 71 enables 5 the sleeve 69 to revolve freely and when the end of the lever 72 carrying said roller is lifted or lowered a corresponding movement is imparted to the sleeve.

The means for leading the threads *a* from the 10 bobbin bracket 60 to the thread guides 1 preferably consists of tubes, such as 75, through which the threads pass and each of which is vertically disposed within the sleeve 69 and bent at its lower end to face outwards and project through a hole 15 or like aperture 69b formed at the bottom of said sleeve. In the alternative arrangement illustrated in Figure 16 for guiding the threads from the source of supply to the thread guides, the guiding means consist of perforated discs 76 spaced axially within the sleeve 69 and supported so as to enable same to be withdrawn upwards from the sleeve to facilitate threading up. Conveniently there are three or more of these discs 20 one fixed at the lower end of a rod 77 suspended eccentrically within the sleeve and the others 25 slidably mounted and resting on shoulders 78a on a rod 78 depending centrally within the sleeve from the bracket or like structure aforesaid. By withdrawing the eccentrically disposed rod 77 the 30 lowest disc is first raised and then brought into contact with the slidable disc immediately above it. The slidable disc upon being slid upwards on the central rod 78 engages the next disc and so on if there are more than three so that eventually all are withdrawn from the sleeve together 35 and the threads *a* can be easily threaded through the perforations therein, after which said discs can be dropped back into the sleeve so that they take up their proper positions. In this arrangement, the sleeve 69 also has holes or like apertures 40 69b at the lower end through which the threads are passed to the thread guides. In order to guide the threads *a* from the lower ends of the tubes, discs or passages as the case may be to the 45 extremities 2 of the guides 1, the said threads are preferably passed through openings formed in a ring 32a pressed into the lower end of the top cylinder 32.

The cylindrical carrier 6 is preferably fitted as 50 shown within the top needle cylinder 32 and the thread guides 1 supply their threads *a* to needles 7 knitting in the bottom cylinder 79 e. g. needles in alternate tricks in 1/1 rib knitting. To enable shogging of the thread guides to be effected the 55 cylindrical carrier 6 is fitted freely within the top cylinder 32 and is driven independently by separate driving gear which may receive its motion from the same shaft as the top cylinder.

Conveniently the pinion 37 hereinbefore referred to is freely mounted on the usual top cylinder driving shaft 36 and meshes with the gear ring 31 on the cylindrical carrier, said pinion having associated therewith the shogging mechanism previously described herein. The gear ring 60 80 on the top cylinder is furnished with grooved segments 81 secured by screws 82 and the cylindrical carrier 6 has a peripheral flange or rib 6a thereon which is received in the grooves in the segments (see Figure 1). The top cylinder 32 65 is driven from the shaft 36 by a pinion 33 adjustably mounted on the shaft as shown in Figure 12 so as to enable the needle tricks in said cylinder to be properly aligned with those in the bottom cylinder 79 as usual.

70 Provision may be made for nullifying the selec-

tive action of the pattern drum or equivalent means on the thread guides. For this purpose I may provide, as indicated clearly in Figures 8, 10 and 11, a vertically movable cam 83 automatically controlled e. g. from the existing timing 5 chain or drum of the machine, for action upon the upwardly extending butts 17 of the guides 1, said cam normally occupying a raised position as shown in full lines in Figure 11 and being lowered for engagement with the butts 17 of selected 10 guides (see Figure 10 and dotted position of cam in Figure 11) so that immediately after selection the said guides are rocked back to their original position. The cam 83 may be used in conjunction with guides, substantially one half of which have 15 long butts and the remainder short butts, so that by lowering the cam wholly the selective action can be nullified entirely and by partly lowering, the selective action can be partly nullified so as to produce half round pattern effects e. g. patterned insteps in the application of the invention to a seamless hose machine. The said cam may also be rendered operative during heel and toe knitting. In the specific arrangement shown in Figures 8, 10, 11 and 19, the nullifying cam 83 is positioned between the two retracting cams 18 and 19 and is formed with a rearward extension 83a which is connected to a slide 84 by means of screws 85. The slide projects through and is adapted to move vertically within a slot 12a in the 20 cam box extension 12 and is formed or provided with retaining flanges 84a. The nullifying cam is adapted to be raised against the action of a spring 86 and to be maintained in this position by a vertically disposed screw or like projection 87 25 mounted in or formed or provided on the free end of a small arm 88 on a vertical link or rod 89 controlled i. e. moved up and down to a slight extent at the appropriate times by linkage (not shown) which is in turn operated by the main 30 controlling mechanism of the machine. The screw or like projection 87, the height of which is preferably adjustable, is arranged to act on an outwardly extending pin 90 on the slide. The link or rod 89 projects upwardly through the top plate 35 40 45 50 55 60 65 70 75 80 85 90 95 100 105 110 115 120 125 130 135 140 145 150 155 160 165 170 175 180 185 190 195 200 205 210 215 220 erative is moved into an operative position at predetermined times by a revolving cam and suitable intermediate connections, and is held inoperative by means of a stop or like part controlled by or from the main controlling mechanism of the machine. Conveniently the stop is associated with the linkage through which the nullifying cam 83 is operated.

In the specific arrangement shown in Figures 17, 18 and 19 and suitable for use in connection with the production of half round effects, such as a plain foot bottom in a seamless half hose, the thread guard 91 which conveniently consists of a thin flat piece of metal somewhat of the shape shown in Figure 17, is rigidly secured to the underside, and at the free end, of an arm 92 pivoted at 93 on the feeder block 94 of the machine. The arm is under the control of a spring 95 which allows it to move into an operative position at the appropriate times, in which position the guard projects through a slot in the feeder plate 96. The movement of the arm 92 is limited in both directions by a screw 97 associated with the feeder block and against which the ends of a slot 92a in the said arm are adapted to abut. The free end of the arm 92 is connected by a rod 98 to a fork or bifurcated member 99 located below a half round cam 100 driven at cylinder speed and conveniently for this purpose mounted on the existing top cylinder driving shaft 36, as shown in Figure 12. On the member 99 is mounted a roller 99' (Fig. 18) which is engaged by the cam 100 as the shaft 36 rotates. To facilitate the connection of the rod 98 to the arm 92, the free end of the latter carries a downwardly extending pin 101. The angular extent of the cam 100 may be varied by providing adjustable sections 100a attached to a hub 100b by screw and slot means 102 so that the in and out movements of the guard 91 can be adjusted to a needle. As will be seen in Figure 19, the guard is held out of action during the knitting of the leg of the article and heels and toes by a block 103 on the vertical link or rod 89 aforesaid. This block has a V notch 103a in it which, when the link or rod is moved slightly downward to render the nullifying cam 83 operative, is presented to a screw or like projection 104 in or on the pivoted arm 92, thereby allowing the guard to move into action and the roller 99' on the fork or bifurcated member 99 to be engaged by the half round cam 100. It will be understood that the guard 91 is moved in and out of action during each course of knitting when operative i. e. it is moved into action for the appropriate partial course and out for the remainder of the course at each revolution of the needle cylinders. When the guard is inoperative the screw or projection 104 engages the block 103 on one side of the notch 103a.

When the thread supplying means are applied to a seamless hose machine a cam, e. g. the cam 83, may be provided for action upon the upwardly extending butts 17 of the thread guides 1 during reverse strokes of reciprocating knitting for the purpose of retracting any thread guides left in a projected position on the change from circular to reciprocating motion. Provision may also be made for disconnecting the driving means for the bracket or like structure which carries the bobbins, cones, spools or reels 58 during reciprocating knitting.

In yet another form, which has been illustrated by way of example in Figure 1, the verge consists of blades or bits 105 fixed radially in a disc

106 freely mounted at the lower end of the sleeve 69 and supported by a bearing ring 107 which is screwed to said sleeve. Conveniently and as shown, the bits are kept in position by a retaining ring 108 and have thickened upper edges 105a for guiding the needles 7 and centralizing the bits. The bits 105 associated with those needles which knit the plain area when the selective actuation of the thread guides 1 is nullified are cut away to allow the thread guard 91 to go in between the needles 7 and associated thread guides when it is rendered operative for the purpose stated.

The pattern drum or equivalent means employed for controlling the operation of the thread guides may be arranged for bodily movement out of its operative position so as to enable patterning to be suspended for prearranged intervals. For example, and as shown in Figures 1 and 19, this movement may be effected from the main controlling means of the machine through the vertical link or rod 89. For this purpose the upper end of the said link or rod is connected to a lever 109 pivoted on or in a small bracket 110 mounted on the top plate 15. The free end of this lever is arranged to project between two stationary guiding blocks 111 on the top plate and an operating member 112, which is bent as shown in Figure 1 for the purpose hereinafter set forth, is carried by the lever. The member 112 extends substantially at right angles to the length of the lever 109 and projects downwardly between a pair of rollers 113 carried by two bifurcated lugs 114 formed on a bracket 115. This bracket is secured, by means of a bolt 116, to a sliding block 117 adapted to be moved horizontally between suitable guideways in the top plate 15. The block 117 is formed with longitudinal flanges 117a which engage the underside of the top plate and prevent the block, and hence also the bracket 115, from being displaced upwardly. The front ends of the bracket 15 and the block 117 are formed with a common open-ended slot 118 for the reception of the upper end of the spindle 20a of the pattern drum 20. The drum 20 is, in effect, suspended from the front end of the bracket 115 and is adapted to be secured in position by a nut 20b which is screwed on to the aforesaid upper end of the spindle 20a. The arrangement just described is such that when the vertical link or rod 89 is moved in a downward direction at the prearranged times, the lever 109 is pulled down with the result that the bent operating member 112 acts between the rollers 113 and moves the bracket 115 together with the sliding block 117 outward, i. e. away from the axis of the machine. In this manner the pattern drum is moved bodily out of its operative position. Conversely, when the said link or rod is returned to its uppermost position, the operating member 112 moves the bracket and the sliding block in the opposite direction so that the drum again moves into its operative position.

Alternatively bluffing means may be provided in association with the racking mechanism for rendering the latter inoperative for the stated purpose. The racking mechanism may, instead of being controlled from the cam 29 aforesaid, be controlled from the timing chain or main control drum of the machine or from an auxiliary chain or drum racked round at every course of knitting.

Instead of the nullifying cam 83 being rendered operative in the manner hereinbefore described

with reference to Figures 8, 10, 11 and 19, the pin 90 on the slide 84 associated with said cam may have a downwardly extending part 90a which is arranged to be acted on by a cam 119 on a segment or, as shown, a sector 120 mounted on the cam box extension 12 and operable by a vertical link or rod (e. g. the link or rod 89) from the main controlling means.

In the modified form of the invention illustrated with reference to Figures 21, 22 and 23, the thread guides 1 are adapted to operate with a movement radially with respect to the needle circle and with movement in the direction of their length in relation to corresponding deflecting elements or bits 121. To this end the thread guides are mounted for both pivotal or rocking movement and sliding movement in the cylindrical carrier 6. Each guide is provided with a lateral lug or like projection 122 for contact with a corresponding deflecting element or bit 121. The said guides, moreover, are movable radially and lengthwise so that upon actuation thereof the lower extremity of each crosses the needle circle first on one side of the corresponding needle or group of needles and then back on the other side by reason of lateral deflection achieved by the lengthwise movement of the guides in relation to the deflecting elements or bits 121 so that the thread supplied to the guide is lapped or wrapped round the desired needle or group of needles. Thus, in this embodiment of the invention the deflecting elements are additional to the needles. The deflecting elements or bits 121 are, in the specific example illustrated in Figure 21, carried in a dial, ring or like member 123 which is attached to the cylindrical carrier 6 so that when the guides 1 are moved lengthwise each guide passes between and engages one of two adjacent elements or bits 121 whereby the lateral deflection is effected. The normal position of a guide in relation to the corresponding element or bit 121 is shown in full lines in Figure 22, while the position of said guide after it has been laterally deflected is indicated in dot and dash lines in the same figure. Instead of being attached to the cylindrical carrier 6, the dial, ring or like member 123 may be independently mounted and, in either event, may be arranged for adjustment in a circular direction so as to enable the elements or bits 121 to be accurately set in relation to the thread guides prior to being fixed in position. Selected guides may be moved radially in the manner hereinbefore described in connection with the first-mentioned form of the invention and cam means of any suitable form (not shown) may be provided for moving selected guides lengthwise to effect lateral deflection thereof and restoring said guides to their original position longitudinally in the cylindrical carrier 6. When this form of the invention is employed, it is preferred to modify the knitting cam system for the needles so that the latter are caused to descend with the guides 1 when the latter are lowered until the lower ends of the selected guides are deflected, but are raised before the said guides are retracted so as to be in a position to receive the threads a to be lapped or wrapped round them. The purpose of this is to prevent the deflected lower ends of the guides from being brought into contact with the needle hooks and possibly damaging same. Conveniently, and as shown in Figure 24, a downward projection 124a is provided upon the usual centre guard cam 124 and an upward projection 125a is provided upon the lower guard cam 125 at the feed or each feed

of the machine according as to whether the machine has a single feed or two or more feeds, i. e. a point or points at which the main yarn or yarns is or are supplied and knitted.

When applied to a seamless hose machine the cam aforesaid which effects downward movement of the guides 1 may be arranged for movement up and down so as to enable it to be raised to an inoperative position at the commencement of reciprocatory knitting so that the guides are not moved up and down during the formation of heels and toes. This cam may be controlled either independently or conjointly with the nullifying cam 83 from the main controlling mechanism of the machine. 15

In a knitting machine for producing seamless hosiery and having the modified form of the invention applied thereto, the reverse stitch cam 126 (Figure 24) may be pivotally mounted owing to the fact that the centre guard cam 124 is formed so as to lower the needles more than usual to enable thread lapping or wrapping to be effected. This cam 126 is connected with the reverse raising picker (not shown) so that should the cam tend to stick after yielding during the forward strokes of reciprocating knitting the cam is positively moved back to the knitting position when the said picker operates. 20

It is within the scope of the invention to provide cam means adapted to operate the thread guides seriatim instead of selectively for the purpose of imparting the radial movement thereto, and to provide in association with the needles to which the patterning threads are to be supplied, needle selecting means, for example pattern controlled variable needle selecting means, for selectively operating the needles so that embroidery or patterning threads are lapped or wrapped around the selected needles in spite of the fact that the guides are operated seriatim as aforesaid. Any suitable needle selecting means, of which there are many known forms, may be used for the intended purpose. 35

In rib knitting on a machine of the superposed needle cylinder type needles may be transferred 45 from the top cylinder 32 to the bottom cylinder 79 while thread lapping or wrapping takes place and said needles may be immediately transferred back to the top cylinder or left in the bottom cylinder. 50

If desired the whole of the patterning head may be arranged so as to be readily removable to facilitate threading up.

The invention is advantageously applicable to a machine of the double cylinder type wherein 55 provision is made for changing from plain to rib knitting and vice versa as it enables hose, half-hose and like articles having a rib top and a plain i. e. non-rib leg or a fully ribbed hose having desired parts thereof ornamented by lap 60 or wrap striping threads producing vertical stripes, broken designs, diagonal and zig-zag effects, clocks, spots and like effects, to be produced in a fully continuous manner on the same machine. The pattern or ornamental effects may be 65 produced in 1/1 and broader ribbed fabric or articles.

What I claim then is:—

1. In combination in a circular knitting machine, double axially opposed needle cylinders, independent needles in said cylinders, patterning mechanism of the kind herein referred to comprising individually movable thread guides consisting of blade-like elements each provided with a thread guiding extremity, said elements being 75

arranged to extend in an axial direction with respect to the needle cylinders, and adapted for movement radially for the purpose of carrying their threads across the needle circle conjointly with relative lateral movement between the thread guiding extremities and the adjacent hooked ends of corresponding needles, whereby the threads are lapped around desired needles, and means for effecting the radial movements of the thread guides.

2. In combination in a circular knitting machine, double axially opposed needle-cylinders, independent needles in said cylinders, patterning mechanism of the kind herein referred to comprising individually movable thread guides consisting of blade-like elements each provided with a thread guiding extremity which extend at an angle from the main portion of the blade, a cylindrical bed in which the thread guides are mounted, said guides being mounted for movement radially for the purpose of carrying their threads across the needle circle, conjointly with lateral deflection of the guides in relation to corresponding needles whereby the threads are lapped around desired needles, and means for effecting the radial movements of the thread guides.

3. In combination in a circular knitting machine, double axially opposed needle cylinders, independent needles in said cylinders, patterning mechanism of the kind herein referred to comprising individually movable thread guides consisting of blade-like elements each provided with a thread guiding extremity which is distorted laterally, said elements being arranged to extend in an axial direction with respect to the needle cylinders and adapted for movement radially for the purpose of carrying their threads across the needle circle conjointly with relative lateral movement between the laterally distorted thread guiding extremities and the adjacent hooked ends of corresponding needles, which movement is produced as the result of co-action of said extremities with the needles whereby the threads are lapped around desired needles, and means for effecting the radial movements of the thread guides.

4. In combination in a circular knitting machine, double axially opposed needle cylinders, independent needles in said cylinders, patterning mechanism of the kind herein referred to comprising individually movable thread guides consisting of blade-like elements each provided with a thread guiding extremity, a cylindrical bed in which the thread guides are mounted, each of said guides having a laterally projecting part and being mounted for movement radially for the purpose of carrying its thread across the needle circle, a series of elements for co-operating with the laterally projecting parts of the thread guides and effecting lateral deflection of the respective guides in relation to corresponding needles during radial movement of the guides whereby the threads are lapped around desired needles, and means for effecting the radial movements of the said thread guides.

5. A combination according to claim 1, wherein means are provided for moving selected thread guides slightly towards the needles to be lapped for the purpose herein set forth.

6. In combination in a circular knitting machine, superposed needle cylinders, independent needles in said cylinders, patterning mechanism of the kind herein referred to comprising a circular series of individually movable thread guides consisting of blade-like elements each provided

with a thread guiding extremity which extends at an angle from the main portion of the blade, a longitudinally tricked cylindrical carrier for the guides located concentrically within the top cylinder, said guides being mounted for movement radially in the carrier for the purpose of carrying their threads across the needle circle conjointly with lateral deflection of the guides in relation to corresponding needles in the bottom cylinder whereby the threads are lapped around desired needles, said guides being also normally positioned vertically above the said needles with their lower extremities disposed radially, and means for effecting the radial movements of the thread guides.

7. In combination in a circular knitting machine, double axially opposed needle cylinders, independent needles in said cylinders, patterning mechanism of the kind herein referred to comprising, individually movable thread guides consisting of blade-like elements which are contrastingly formed and each provided with a thread guiding extremity, a cylindrical bed in which the thread guides are mounted for rocking movement, a series of selecting cams whereby thread guides are selected and moved radially in one direction for the purpose of carrying their threads across the needle circle conjointly with relative lateral movement between the thread guiding extremities and the adjacent hooked ends of corresponding needles whereby the threads are lapped around desired needles, means for automatically selecting said cams for action upon the thread guides according to pattern requirements, and cam means for moving selected guides radially in the opposite direction.

8. In combination in a circular knitting machine, double axially opposed needle cylinders, independent needles in said cylinders, patterning mechanism of the kind herein referred to comprising individually movable thread guides consisting of blade-like elements each provided with a thread guiding extremity, said elements being arranged to extend in an axial direction with respect to the needle cylinders and adapted for movement radially for the purpose of carrying their threads across the needle circle conjointly with relative lateral movement between the thread guiding extremities and the adjacent hooked ends of corresponding needles, whereby the threads are lapped around desired needles, means for effecting the radial movements of the thread guides, and means for varying the relative positions of the thread guides and the needles laterally so that said guides can supply threads to different needles.

9. In combination in a circular knitting machine, double axially opposed needle cylinders, independent needles in said cylinders, patterning mechanism of the kind herein referred to comprising individually movable thread guides consisting of blade-like elements each provided with a thread guiding extremity, said elements being arranged to extend in an axial direction with respect to the needle cylinders and adapted for movement radially for the purpose of carrying their threads across the needle circle conjointly with relative lateral movement between the thread guiding extremities and the adjacent hooked ends of corresponding needles, whereby the threads are lapped around desired needles, means for effecting the radial movements of the thread guides, and means for nullifying the patterning action and restricting the patterning effect to prearranged needles.

10. In combination in a circular knitting ma-

- chine, double axially opposed needle cylinders, independent needles in said cylinders, patterning mechanism of the kind herein referred to comprising individually movable thread guides consisting of blade-like elements each provided with a thread guiding extremity which extends at an angle from the main portion of the blade, said guides being mounted for movement radially for the purpose of carrying their threads across the needle circle, conjointly with lateral deflection of the guides in relation to corresponding needles whereby the threads are lapped around desired needles, means for effecting the radial movements of the thread guides, a cylindrical carrier in which the thread guides are mounted, a sleeve depending from an upper part of the machine and upon which the cylindrical carrier is rotatably mounted, and means for driving the cylindrical carrier at a speed equal to the cylinder speed.
- 20 11. In combination in a circular knitting machine, double axially opposed needle cylinders, independent needles in said cylinders, patterning mechanism of the kind herein referred to comprising individually movable thread guides consisting of blade-like elements each provided with a thread guiding extremity which extends at an angle from the main portion of the blade, said guides being mounted for movement radially for the purpose of carrying their threads across the needle circle, conjointly with lateral deflection of the guides in relation to corresponding needles whereby the threads are lapped around desired needles, means for effecting the radial movements of the thread guides, a number of bobbins from which the additional threads are supplied to the thread guides, a bracket arranged above the cylindrical bed and adapted to carry the bobbins, and guiding means for the threads arranged within said cylindrical bed.
- 25 12. A combination according to claim 11, wherein the driving member consists of a reel slidably keyed on the driving shaft and furnished with opposed formations and wherein the said means for axially adjusting the driving member comprise a pattern controlled sliding member carrying rollers adapted to engage the opposed formations and means for moving the sliding member to different positions radially with respect to the axis of the shaft.
- 30 13. In combination in a circular knitting machine, double axially opposed needle cylinders, independent needles in said cylinders, patterning mechanism of the kind herein referred to comprising individually movable thread guides consisting of blade-like elements which are contrastingly formed and each provided with a thread guiding extremity, a cylindrical bed in which the thread guides are mounted for rocking movement, a series of selecting cams whereby thread guides are selected and moved radially in one direction for the purpose of carrying their threads across the needle circle conjointly with relative lateral movement between the thread guiding extremities and the adjacent hooked ends of corresponding needles whereby the threads are lapped around desired needles, means for automatically selecting said cams for action upon the thread guides according to pattern requirements, cam means for moving selected guides radially in the

opposite direction, means for shogging the thread guides laterally over the needles so that said guides can supply threads to different needles, said shogging means being controlled from the same source as the selective operation of the thread guides.

14. In combination in a circular knitting machine, double axially opposed needle cylinders, independent needles in said cylinders, patterning mechanism of the kind herein referred to comprising individually movable thread guides consisting of blade-like elements each provided with a thread guiding extremity which extends at an angle from the main portion of the blade, a cylindrical bed in which the thread guides are mounted, said guides being mounted for movement radially for the purpose of carrying their threads across the needle circle, conjointly with lateral deflection of the guides in relation to corresponding needles whereby the threads are lapped around desired needles, means for effecting the radial movements of the thread guides, a number of bobbins from which the additional threads are supplied to the thread guides, a bracket arranged above the cylindrical bed and adapted to carry the bobbins, and guiding means for the threads arranged within said cylindrical bed.

15. In combination in a circular knitting machine, double axially opposed needle cylinders, independent needles in said cylinders, patterning mechanism of the kind herein referred to comprising individually movable thread guides consisting of blade-like elements each provided with a thread guiding extremity, said elements being arranged to extend in an axial direction with respect to the needle cylinders and adapted for movement radially for the purpose of carrying their threads across the needle circle conjointly with relative lateral movement between the thread guiding extremities and the adjacent hooked ends of corresponding needles, whereby the threads are lapped around desired needles, means for effecting the radial movements of the thread guides, means for nullifying the patterning action and restricting the patterning effect to prearranged needles, a movable thread guard, and means for moving said guard and presenting it between the hooks of the needles and the thread guides at the selecting location at predetermined times for the purpose herein set forth.

16. In combination in a circular knitting machine, controlling mechanism for said machine, double axially opposed needle cylinders, independent needles in said cylinders, patterning mechanism of the kind herein referred to comprising individually movable thread guides consisting of blade-like elements each provided with a thread guiding extremity, said elements being arranged to extend in an axial direction with respect to the needle cylinders and adapted for movement radially for the purpose of carrying their threads across the needle circle conjointly with relative lateral movement between the thread guiding extremities and the adjacent hooked ends of corresponding needles, whereby the threads are lapped around desired needles, means for effecting the radial movements of the thread guides, means for nullifying the patterning action and restricting the patterning effect to prearranged needles, a movable thread guard adapted to be presented between the hooks of the needles and the thread guides at the selecting location at predetermined times, means for normally holding the thread guard inoperative, a cam for moving the thread guard into an opera-

tive position at said times, and means for rotating said cam in timed relation with the needle cylinders.

17. In combination in a circular knitting machine, double axially opposed needle cylinders, independent needles in said cylinders, patterning mechanism of the kind herein referred to comprising individually movable thread guides consisting of blade-like elements each provided with a thread guiding extremity, a cylindrical carrier in which the thread guides are slidably mounted, each thread guide having a laterally projecting part and being also mounted for movement radially for the purpose of carrying its thread across the needle circle, a series of elements arranged in proximity to the thread guiding extremities of the thread guides and adapted to co-operate with the laterally projecting parts of said guides to effect lateral deflection of the respective guides in relation to corresponding needles as the result of relative lengthwise movement between the guides and the said elements, means for effecting the radial movements of the guides and cam means for moving the guides lengthwise to effect the required lateral deflection thereof and to restore said guides to their original position longitudinally in conjunction with the radial movements whereby the threads are lapped around desired needles.
18. In combination in a circular knitting machine, double axially opposed needle cylinders, independent needles in said cylinders, patterning mechanism of the kind herein referred to comprising individually movable thread guides consisting of blade-like elements each provided with a thread guiding extremity, a cylindrical carrier in which the thread guides are slidably mounted, each thread guide having a laterally projecting part and being also mounted for movement radially for the purpose of carrying its thread across the needle circle, a series of elements arranged in proximity to the thread guiding extremities of the thread guides and adapted to co-operate with the laterally projecting parts of said guides to effect lateral deflection of the respective guides in relation to corresponding needles as the result of relative lengthwise movement between the guides and the said elements, means for effecting the radial movements of the guides, cam means for moving the guides lengthwise to effect the required lateral deflection thereof and to restore said guides to their original position longitudinally in conjunction with the radial movements whereby the threads are lapped around desired needles, and means for moving the needles lengthwise with the guides until the thread guiding extremities are deflected and for moving said needles in the opposite direction before the guides are returned to their original positions subsequent to carrying their threads across the needle circle so that the needles are in a position to receive the threads to be lapped.
19. In combination in a circular knitting ma-

chine, double axially opposed needle cylinders, independent needles in said cylinders, patterning mechanism of the kind herein referred to comprising a circular series of individually movable thread guides, a grooved cylinder in which said thread guides are pivotally and slidably mounted, each thread guide consisting of a blade-like element and being furnished with a thread guiding extremity which is laterally distorted and extends at an angle from the main portion of the blade, a fulcrum, at least two front butts above the fulcrum, and an upwardly extending butt at the opposite end to the yarn engaging extremity, selecting means arranged above the fulcrum for action on the front butts of the thread guides whereby selected jacks are pressed inward above the fulcrum so that their thread guiding extremities are projected radially outward with respect to the needles whereby the threads are carried across the needle circle from the inside to the outside conjointly with lateral deflection of the selected guides in one direction in relation to corresponding needles which deflection is produced as the result of co-action of the laterally distorted thread guiding extremities with adjacent hooked ends of the corresponding needles, cam means which by action on the said upwardly extending butts move the selected thread guides radially in the opposite direction conjointly with lateral deflection of said guides in the opposite direction, whereby the threads are lapped around desired needles, and cam means for action on one of the front butts of each of the selected guides whereby the latter are slightly lowered and then raised, for the purpose herein set forth.

20. A thread guide for use in patterning mechanism of the kind herein referred to comprising a stem, a thread guiding extremity at one end of and extending at an angle from the stem, said extremity being distorted laterally, at least one butt on one edge of the stem for engagement with a selecting cam, said stem having a fulcrum point on the opposite edge, a main butt above the fulcrum point for engagement with a cam for imparting endwise movement to the thread guide, and an upwardly extending butt at the end of the guide remote from the thread guiding extremity for engagement with an actuating cam.

21. A thread guide for use in patterning mechanism of the kind herein referred to, comprising a stem, a thread guiding extremity at one end of the stem, a laterally projecting part near the thread guiding extremity for co-operation with a deflecting element, at least one butt on one edge of the stem for engagement with a selecting cam, a main butt on said edge for engagement with a cam for imparting endwise movement to the thread guide, and an upwardly extending butt at the other end of the stem for engagement with an actuating cam.

ALFRED WOODWARD KENT.
